CLAIM

The ornamental design for a pulsator washing machine, as shown and described.

DESCRIPTION

The patent or application file contains at least one drawing executed in color. Copies of this patent or patent application publication with color drawing(s) will be provided by the Office upon request and payment of the necessary fee.

1. Pulsator washing machine

1.1 : Front

1.2 : Back

1.3 : Left

1.4 : Right

1.5 : Top

1.6 : Bottom

1.7 : Perspective

1.1 is a front elevation view of a pulsator washing machine of our new design; 1.2 is a back elevation view thereof; 1.3 is a left side elevation view thereof; 1.4 is a right side elevation view thereof; 1.5 is a top plan view thereof; 1.6 is a bottom plan view thereof; and 1.7 is a perspective view thereof. The product incorporating the design is used for washing clothes; the drawing designated to best show the essential features of the design is 1.7.

The portions of the washing machine shown by coloring in Figures 1.2 and 1.6 form no part of the claimed design.
